UNITED STATES PATENT OFFICE.

RICHARD DALTON, OF WILMETTE, ILLINOIS.

WAGON.

SPECIFICATION forming part of Letters Patent No. 278,408, dated May 29, 1883.

Application filed November 3, 1882. (No model.)

To all whom it may concern:

Be it known that I, RICHARD DALTON, a citizen of the United States of America, residing at Wilmette, in the county of Cook and State of Illinois, have invented a new and useful Improvement in Wagons for use in Soft Ground, of which the following is a specification.

This invention relates to hay-trucks and other vehicles for use in soft ground; and it consists in a frame of suitable form supported by one or more broad wheels or rollers at one end, and a smaller pivoted wheel or roller at the other end adapted to be easily removed, substantially as hereinafter more fully set forth.

In order to enable others skilled in the art to which my invention appertains to make and use the same, I will now proceed to describe its construction and operation, referring to the accompanying drawings, in which—

Figure 1 represents a side elevation of my invention arranged for carrying hay. Fig. 2 is a plan view of the same, partly broken away to show the construction of the wheel. Fig. 3 is a modification of the small wheel. Fig. 4 is a side view of the same, showing a different construction of the end of the wheel or roller. Fig. 5 is a cross-section of the same with the wheel or roller in elevation. Fig. 6 is a view showing a slight modification of the device adapted to different work. Fig. 7 is a detail sectional view of the bearing for the roller or wheel.

A represents a rectangular frame provided near the center with journal-boxes *a* on its under sides, in which is journaled the axle of a broad wheel or roller, *B*. This wheel may be made in various ways for the different kinds of ground on which it is to be used.

Figs. 1 and 2 show a number of ordinary wagon-wheels, *b*, having hubs, spokes, and felloes, and connected at short intervals by planks *b'*, which are secured with iron bands or tires, and form a wheel or roller extending across the machine from one side of the frame to the other. This wheel or roller is secured firmly to the axle, and turns with it in the bearings *a*.

The frame *A* is floored or boarded over, and this floor or bottom *A'* passes over the top of the broad wheel, as seen in Figs. 1 and 3, sup-

ported by a suitable frame-work. The forward end of this frame is furnished with an upright or post, *C*, at each corner, which is suitably braced and provided with a series of holes, *c*, in one of which is secured a clamp or clevis, *C'*, to which the team is attached. These holes give an easy adjustment for teams of different size, and the great height of the draft attachment aids greatly in keeping the animals from sinking too deeply into the ground. In very soft ground it will be found advantageous to form the main wheel as shown in Figs. 4 and 5, which represent the ends of the wheel boarded up, similar to the head of a barrel, and the connecting-boards *b'* are placed close together, and secured, as before, by any desired number of bands or tires.

The rear end of the main frame *A* is supported by an inclined bar, *D*, having its lower end resting upon a small wheel, *D'*, formed like the large wheel *B*, as seen in Figs. 1 and 2, or as seen in Fig. 3 upon a caster-wheel.

The frame or truck described is, in soft ground, prevented by the broad wheels or rollers from sinking to any depth, as would be the case with ordinary vehicles, and the great height of the draft attachment aids materially in holding the team up. The frame may be provided with the usual "rack" for hauling hay or similar material, or with any other sides suitable for different uses. When used upon the road or hard ground in going from one field to another the bar *D*, with its caster-wheel, is easily removed and the frame attached to the reach and front wheels of an ordinary wagon, and may thus be easily managed.

For drawing lumber or other long material I usually use two of the broad wheels or rollers *B* *B'*, and allow the load to rest between them, as seen by Fig. 6. Where two of these wheels are used, as thus described, I usually prefer to form them of two felloes or rims secured to the hub by spokes which extend from the felly or rim on one side of the wheel to the hub at the opposite side, as seen by dotted lines in Fig. 6, and the spokes crossing each other midway between the hub and the rim effectually brace the wheel in all directions.

To prevent the accumulation of earth or mud upon the wheels *B*, I provide the device in rear of the said wheel with a scraper, *E*, ex-

tending across the machine from side to side a short distance above the ground, and suspended, by brace-rods *ee*, from the side bars of the main frame.

5 The machine is simple, extremely cheap, and of great utility, enabling the user to draw heavy loads upon ground so soft as to be inaccessible to ordinary wagons, and with but little strain upon the team. The device in soft 10 ground is easier and better drawn with the team attached to the end nearest to the large wheels, as shown, but in hard soil is better managed when the draft is at the opposite end.

Having thus fully described my invention, 15 what I claim as new, and desire to secure by Letters Patent, is—

1. In a wagon adapted for use in soft ground, the combination, with the main frame *A*, having its floor arched over the main wheels, and 20 provided with elevated draft attachments, of one or more main rollers or wheels, *B*, con-

structed substantially as herein described, and journaled in boxes upon the frame *A*, and a smaller removable pivoted wheel or roller, *D'*, under the rear of the machine, substantially 25 as and for the purpose described.

2. A wagon adapted for use in soft ground, consisting, essentially, in the main frame *A*, having draft-posts *C*, provided with holes *c* and clevises *C'*, the wheel or roller *B*, journaled 30 in boxes *a* on the main frame, the pivoted wheel or roller *D'*, attached to the removable bar *D*, and the scrapers *E*, secured by braces *e*, all constructed and arranged to operate substantially as shown and described. 35

In testimony whereof I affix my signature in presence of two witnesses.

RICHARD DALTON.
